KNOCKDOWN FURNITURE

Valerie F. Blake, New York, N. Y.

Application January 31, 1933, Serial No. 654,408

2 Claims. (Cl. 311—79)

This invention relates to tables and similar articles of furniture.

The objects of the invention are to provide a table or the like, in a light, inexpensive, folding or knockdown form, which can be stored and shipped in compact flat shape, which can be quickly and easily set up without tools or exercise of any skill and which may be constructed of cardboard, corrugated board or similar inexpensive flexible material and be so braced and secured when set up as to constitute a rigid, durable and practical structure.

Additional objects and the various novel features of the invention by reason of which such objects are attained, will all appear as the specification proceeds.

The drawing accompanying and forming part of the specification illustrates certain practical commercial embodiments of the invention, but it is to be understood that the structure may be modified and changed all within the broad intent and scope of the claims.

Fig. 1 is a perspective view illustrating a table construction and showing the two base parts assembled and the table top as about to be interlocked therewith, the arrows in this view indicating how the assembled base parts may be hinged flat together without disassembling them.

Figs. 2 and 3 are face views on a smaller scale illustrating the complementary base parts.

Fig. 4 is an end view illustrating how the base members and the table top may each be folded into smaller compass and the three parts be packed in a relatively small flat bundle.

Fig. 5 is an end view illustrating folding of the base members into flat relation by the hinging movement indicated by the arrows in Fig. 1.

Fig. 6 is an enlarged broken and sectional detail, illustrating the interlocking engagement between table top and base members.

Fig. 7 is a similar view illustrating a modified construction.

As shown in Fig. 1, the table consists of simply three parts, the two companion base members 8, 9 and the top member 10. These several members may be of various sizes and shapes.

In this particular disclosure, all three members of the table are made of corrugated board, as appears at the edges of the members at 11. For structural reasons, the base members are arranged with the corrugations running vertically and the top member is disposed with the corrugations extending inclinedly to both the base members.

The base members are connected by slotting

one up from the bottom as indicated at 12, Fig. 8, and the other down from the top as indicated at 13, Fig. 3, and engaging one over the other as in Fig. 1, so that the separated parts of one come opposite a solid portion of the other.

The top member is interlocked with the two base members by means of slots 14, in the corners of the top member, taking over upstanding lugs 15, on the outer corners of the base members.

The lugs or keys 15 may be formed so as to automatically lock the table top in place thereon, as by forming them somewhat undercut as indicated at 16, in Fig. 6 and by cutting the slots just deep enough so as to require the forcing down of the table top over these lugs, the springiness and flexibility of the material enabling this interlocking action.

In Fig. 7, it is shown that the locking and positioning slots in the table top need not be cut through to the edges of the top and may be formed as diagonally disposed slot-like holes 14a therethrough. This leaves a continuous rim of material at 17, about the edge of the top at the outside of the locking lugs 15. This view also shows how the lugs 15 may be set inward from the outer edges of the base members, so as to leave a supporting shoulder 18, at the outside of the lugs for support of the continuous rim portion 17 of the top. The lugs 15 in this last described construction may be undercut at the outer edges as indicated at 16a, so as to hold the top down by the outer rim portion of the same and, as also indicated in Fig. 7, the lugs may be undercut at both edges to lock the table top more firmly in place. Fig. 7 illustrates as well, the fact that the locking lugs 15 need extend but slightly, if at all, above the table surface.

The table may be made in various heights, such as best suited to card playing, beach parties, picnic or other purposes and both the top and base members may be made in various ornamental shapes and sizes. Thus, the top may be circular, oval or oblong instead of the square shape shown. The corrugated board of which the parts are made, may be specially painted, printed, covered, varnished, or otherwise treated to produce artistic effects and, or, to render the same liquid-proof, fire-resisting or the like.

The table is quickly set up by simply matching the slotted portions of the two base members and slipping them together in the rectangular relation shown in Fig. 1, after which the top is forced down over the lugs of the base members, whereupon the top locks the base members in their outstanding relation and becomes in turn locked to

said base members. In this locked relation of the parts, the table may be handled as a single unit and without coming apart.

To fold the table, it is only necessary to lift off the top, forcing it back over the rounded holding shoulders of the holding lugs and when clear, the two base members may be swung together as indicated by the arrows, Fig. 1, about the central connected portions, as a pivot to the flat folded condition indicated at Fig. 5, where the split or separated portions 8a, 9a of each member will overlie opposite faces of solid or uncut portions of the other member, the flexibility of the material permitting this action without any breaking or tearing. If desired, the base members can be readily entirely separated, but usually the table may be taken down and stored by simply removing the top, swinging the two base members flat together and then placing the top flat over the folded base pieces, the whole then constituting a flat bundle, which may be readily stored behind a door or the like.

If it is desired to pack or store the structure in smaller space, the base members may be folded on themselves by scoring the solid portions of the same, in line with the cuts as indicated at 19, Figs. 2 and 3, to form suitable hinges for the purpose. Similarly, the top may be scored or otherwise be given a hinging line 20. Fig. 4, shows how when thus folded on themselves the members may be packed in smaller space, width considered. The hinge lines 19 and 20 extend longitudinally of the corrugations and so enable the desired hinging movements without cutting across or weakening the longitudinal stability of the corrugations.

For shipment and for storage before sale, the three parts may be packed in the closely folded condition illustrated in Fig. 4 and thereafter when a table is taken down for putting away, it may be folded by simply removing the top and hinging the base members together as in Fig. 5, leaving the parts then in condition to be more easily set up as a table.

Where the interengaging positioning and locking lugs and slots are equidistantly spaced, as here illustrated, the table top is both interchangeable all around and reversible face-for-face. This same reversibility and interchangeability can be carried out with circular and other shapes of table tops and to a lesser extent, can be carried out with elongated and other shapes of tops. The flexibility and resiliency of the material is an ad-

vantage in the quick setting up and fitting of the parts and the positive interlocking of the constituent parts provides a relatively sturdy rigid structure, even though the several members be of rather light and somewhat flimsy material. The interlocking bracing relations of the members provide sufficient strength to enable the utilization of the invention for stools, stands and the like, as well as for tables. The slots in the edge portion of the table top definitely space and steady the upper outer corners of the base members, where the need for bracing is greatest. The scoring 18 in the solid portion of one base member has a tendency to center and hold the split portions of the other base member, thereby bracing such split portions to such extent.

What is claimed is:

1. A table or the like, comprising folding base members slotted inward from opposite ends and having hinging scores extending from the inner ends of the slots therein, whereby when interlocked by endwise engagement, separated portions of one base member will come opposite and be located by scored portions in the face of the other base member and a folding top member having an intermediate hinging score, said folding top member being supported by said base members and having interlocking engagement at its edges with the outer corner portions of the base members, to thereby definitely locate and secure said outer corner portions, and said interlocking engagement between the edges of the folding top member and outer corner portions of the base members also holding said folding top member in its spread open position, wherein it holds the folding base members fixedly spaced in spread open relation.

2. A table or the like, comprising base members of corrugated board arranged with the corrugations extending vertically and slotted inwardly from opposite ends to enable endwise interlocking engagement of the same, undercut lugs at the outer corners of said base members providing locking shoulders at the undercut portions of the same and a top member of corrugated board having a folding score extending longitudinally of the corrugations and having slots at the corners of the same engageable over said lugs and held by the locking shoulders at the undercut portions of said lugs in the spread open position where it braces the base members and is braced thereby.

VALERIE F. BLAKE.
